(57) **CLAIM**

The ornamental design for a work platform, as shown and described.

DESCRIPTION

FIG. 1 is a front perspective view of a work platform showing our new design in an open position;

FIG. 2 is a top plan view thereof;

FIG. 3 is a side elevational view thereof, the view from the other side being a mirror image of FIG. 3;

FIG. 4 is an end elevational view thereof, the view from the other side being a mirror image of FIG. 4;

FIG. 5 is a bottom plan view thereof;

FIG. 6 is a perspective view thereof in a closed position;

FIG. 7 is a top plan view thereof in a closed position;

FIG. 8 is a side elevational view thereof in a closed position, the view from the other side being a mirror image of FIG. 8;

FIG. 9 is a bottom plan view thereof in a closed position; and,

FIG. 10 is an end elevational view thereof in a closed position, the view from the other side being a mirror image of FIG. 10.

The broken lines shown in the figures are included for the purpose of illustrating portions of the ladder top and form no part of the claimed design.

1 Claim, 8 Drawing Sheets
